United States Patent Office

Des. 228,590
Patented Oct. 16, 1973

228,590

DISPLAY STAND OR THE LIKE

Peter J. Purpura, Corning, N.Y., assignor to Corning Glass Works

Filed May 14, 1971, Ser. No. 143,735

Term of patent 14 years

Int. Cl. D6—06

U.S. Cl. D6—29

Fig. 1

Fig. 3

Fig. 2

FIG. 1 is a top plan view of a display stand or the like embodying my new design.

FIG. 2 is a front elevational view thereof.

FIG. 3 is a side elevational view taken along line 3—3 of FIG. 1.

I claim:

The ornamental design for a display stand or the like, as shown.
